UNITED STATES PATENT OFFICE.

ELI CINDEL, OF NEMO, SOUTH DAKOTA.

RULE OR TOOL HOLDER FOR GARMENT POCKETS.

Application filed July 25, 1922. Serial No. 577,393.

To all whom it may concern:

Be it known that I, ELI CINDEL, a citizen of the United States, residing at Nemo, in the county of Lawrence and State of South Dakota, have invented certain new and useful Improvements in Rule or Tool Holders for Garment Pockets, of which the following is a specification.

This invention relates to attachments for the pockets of garments for preventing the loss of articles placed therein, and the primary object of the invention is to provide a novel device removably associated with a pocket of a mechanic's garment for preventing the loss of a rule or tool placed therein.

Another object of the invention is to provide means for spreading the pockets of a garment laterally so as to bring the front and rear walls thereof into close proximity whereby said walls will frictionally engage objects placed therein to prevent the accidental loss thereof.

A further object of the invention is to provide a novel means for preventing the loss of a rule from the rule pocket of a mechanic's garment comprising a resilient clip arranged to spread the pocket laterally for bringing the front and rear faces of the pocket into intimate contact with the opposite faces of the rule, and means for engaging the pocket to hold the spring clip against displacement therefrom.

A further object of the invention is to provide a resilient U-shaped clip for engaging the side walls of a pocket to spread the same laterally, and an attaching clip carried by the bight portion of the U-shaped clip for engaging the outer face of the pocket for holding the U-shaped clip in position, said attaching clip forming a guide and wear surface to facilitate the entrance of the rule into the pocket.

A further object of the invention is to provide a removable loss preventing device for pockets of the above character, which is durable and efficient in use, one that is simple and easy to manufacture, and one which can be placed upon the market at a low cost.

With these and other objects in view, the invention consists in the novel construction, arrangement and formation of parts, as will be hereinafter more specifically described, claimed and illustrated in the accompany-

ing drawings, forming a part of this specification, in which drawings:

Figure 1 is a view of the improved loss preventing pocket showing the same applied to the rule pocket of a pair of overalls.

Figure 2 is a vertical longitudinal section through the rule pocket on an enlarged scale, showing the improved loss preventing device associated therewith.

Figure 3 is a detail perspective view of the improved loss preventing device removed from the pocket.

Figure 4 is a transverse section through the pocket taken on the line 4-4 of Figure 1, showing the improved loss preventing device applied thereto illustrating the position of the pocket when the same is stretched by said device for gripping a rule.

Referring to the drawings in detail, wherein similar reference characters designate corresponding parts throughout the several views, the letter A generally indicates the improved loss preventing device; B, a rule pocket of a garment C; and D, a rule in said pocket.

While I have shown the improved device applied to the rule pocket of a pair of overalls, it is to be understood, of course, that the improved device A can be used with pockets of other garments for preventing the loss of any article therefrom.

The rule pocket B is attached to the overalls C in the ordinary manner, and is of the ordinary construction, and includes the front wall or face 5, and the rear wall or face 6. The rear wall or face 6 in the example shown forms a part of the overalls. The side edges of the front wall or face 5 are turned inwardly, as at 7 in the ordinary manner and sewed to the rear wall 6.

The overalls C and the rule D are of course of the ordinary construction, and it is deemed superfluous to give a detailed description thereof.

The improved attachment A comprises essentially the pocket spreading portions E and pocket engaging or attaching portion F.

The pocket spreading portions E includes the resilient U-shaped body 10 normally inverted, comprising the resilient legs 11 and 12 diverging downwardly and their connecting body or bight portion 13. This U-shaped portion 10 is preferably formed of

resilient wire of the desired gauge and owing to the inherent resiliency of the metal from which the portion 10 is formed, the legs 11 and 12 normally tend to spread outwardly in opposite directions. In order to facilitate the insertion of the portion 10 within the pocket B, the free terminals of the legs 11 and 12 are provided with inwardly extending angularly related feet 14, 10 which form guide members for engaging the sides of the pockets.

The means F is utilized for positively holding the pocket spreader E in position, and is formed of a single ribbon or strip of 15 resilient metal.

The attaching means F comprises the relatively long body portion 15, the bent back intermediate portion 16, which terminates below the upper edge of the body portion 15 20 and a spring tongue 17 bent downwardly from the upper end of portion 16. The spring tongue 17 terminates in an arcuate extension 18, which facilitates the placing of the clip in engagement with the front wall 25 or surface 5 of the pocket C. The upper edge of the body portion 15 is rolled about the bight or connecting portion 13 of the clip E as at 19 and serves as means for securing the attaching portion to the clip or 30 pocket spreader E.

In use of the improved loss preventing device, the legs 11 and 12 are grasped by the fingers and pressed inwardly, and the clip E is then pushed into the pocket and the front wall 5 is placed intermediate the tongue 17 and the intermediate portion 16. The tongue 17 will frictionally engage the pocket and thus preclude movement of the clip E in the pocket. When the legs 11 and 40 12 are released, the same will spring outwardly and exert a tension on the side edge of the pocket and thus spread the same and bring the front and rear faces of the pockets 5 and 6 toward each other.

45 The U-shaped body being inverted and its legs 11 and 12 diverging downwardly, the intermediate portion of the front and rear faces of the pocket will be stretched to a greater degree than the top of the pocket, 50 and, hence it will be comparatively easy to insert the rule D or other object into the pocket,—easier than if the side edges were uniformly spread apart or the upper part of the pocket stretched; yet as the rule is 55 forced into the pocket there is a gradual increasing resistance set up by the stretched intermediate portion of the front and rear faces of the pocket which holds the rule or other object from falling out. The rear or 60 body portion 15 of the attaching means F also forms means for frictionally engaging the rule so as to prevent loss of the same from out of the pocket and this body portion forms a guide for the rule or other article 65 when the same is being placed in the pocket

and also acts as a wear surface to prevent the tearing or wearing out of the front face 5 of the pocket.

From the foregoing description, it can be seen that an exceptionally simple device 70 has been provided for removable association with pockets for preventing the accidental displacement of articles placed in the pocket.

Changes in details may be made without departing from the spirit or scope of this 75 invention; but,

I claim:

1. The combination with a pocket, of an inverted U-shaped clip disposed with the legs thereof engaging the opposite edges 80 of the pocket at the interior thereof to stretch the front and back of the pocket, and a second clip carried by the bight portion of the first mentioned clip and engaging the upper portion of the pocket to dispose the bight portion above the opening of the pocket.

2. The combination with a pocket, of an inverted U-shaped clip disposed with the legs thereof engaging the opposite edges of the 90 pocket at the interior thereof to stretch the front and back of the pocket, and means for retaining the bight portion of the clip exposed above the opening of the pocket.

3. The combination with a garment pocket, of a loss preventing device therefor including a resilient clip embodying a pair of resilient, normally downwardly diverging legs, and a connecting bight portion at the upper ends of said legs, the legs being adapted to engage the opposite side edges of the pocket at a distance below the opening thereof to spread the pocket laterally and force the front and rear faces of the pocket into frictional contact with an article placed 105 therein to a greater degree below the opening of the pocket than at the top thereof, and a resilient clip associated with the bight portion of the first mentioned clip for forcibly engaging the front wall of the pocket to hold 110 the loss preventing device in position against accidental displacement.

4. The combination with a garment pocket, of a loss preventing device therefor including a resilient U-shaped clip embodying diverging legs and a connecting body portion, inwardly extending feet formed on the free terminals of the legs, and an attaching clip associated with the U-shaped clip embodying means for frictionally engaging the front wall of the pocket and a guide face for facilitating the entrance of an article 120 into the pocket.

5. As a new article of manufacture, a loss preventing device for pockets comprising a 125 U-shaped clip including a pair of normally diverging legs and a connecting body portion, and a pocket engaging attaching clip carried by the bight portion of the U-shaped clip.

6. As a new article of manufacture, a loss preventing device for garment pockets comprising a U-shaped clip for spreading the pockets laterally including a pair of normally diverging legs and a connecting bight portion, inwardly extending guide feet formed on the free terminals of the legs, and an attaching clip associated with the body portion of the U-shaped clip including a body portion, a bent back intermediate portion, and a resilient bent down tongue for engaging the pocket, the body portion defining a wear surface for the pocket, a guide means for facilitating the entrance of an article in the pocket, and means for engaging an article to prevent movement thereof in the pocket.

ELI CINDEL.
